APPARATUS FOR FEEDING PAPER SHEETS

Application filed September 22, 1928. Serial No. 307,702.

With apparatus for feeding paper sheets, it is essential, for attaining a reliable sheet feed to the printing machine, to retard the movement of certain rotary parts thereof during part of their revolution.

The present invention relates to an improved device for attaining this object in view. According to the same, the casing of a differential gearing is set in reciprocating motion by arranging on the main shaft of the apparatus an eccentric that is in connection with a toothed sector, of which the teeth are in gear with a toothing on the casing of the differential gearing. Thereby, the planet wheels are turned, once, in the rotary direction of said main shaft and, then, in opposite direction, whereby the resulting variation in the speed of the driven wheel during one revolution takes place after a sine curve.

By the improved device, particularly, sudden speed changes and shocks resulting therefrom are avoided; the speed changes taking place in a uniform and smooth way, which is of great advantage for the working of the machine, especially of high-speed machines.

The accompanying drawings illustrates the improved device by way of example:

Fig. 1 is a side view partly in section thereof,

Fig. 2 is an end view thereof,

Figs. 3 and 4 are cross-sections on the line III-IV of Fig. 1, respectively in the direction of arrow 3 and of arrow 4.

On the main shaft *a* of the sheet feeding apparatus a spur wheel *b* is keyed and in gear with a pinion *c* on an axle *d* revolvably mounted in the two-part casing *e*. Said axle *d* carries a toothed wheel *f* of somewhat larger diameter than that of the pinion *c*. On the main shaft *a*, furthermore, a rotary sleeve *h* is loosely mounted and fitted at its inner end with a toothed wheel *g* and at its outer end with a driving chain wheel *i*, the two-part casing *e* being loosely mounted on the sleeve *h* and the two toothed wheels *f*, *g* meshing with one another through an intermediary gear *k* revolvably mounted on a bolt *l* fixed in one side wall of the casing *e*.

Assuming that the casing *e* is in fixed or stationary position, the spur wheel *b* would turn the pinion *c* and thereby the toothed wheel *f*, intermediary gear *k*, toothed wheel *g*, and chain wheel *i*.

According to the invention, however, the casing *e* is not fixed or stationary but turnable about the main shaft *a*. For attending a uniform reciprocation of the same, the following arrangement is provided:

On the main shaft *a* an eccentric *m* is keyed, of which the loose outer frame *n* carries a rod *o* linked to a lever arm *p* on a shaft *q*, that is fitted with a toothed sector *r* in gear with another toothed sector *s* on the casing *e*. With a rotation of the main shaft *a* the rod *o* and thus the lever *p* are uniformly rocked, which motion is transmitted through the toothed sectors *r*, *s* to the casing *e*. Consequently, the gears *c*, *f*, *k* are turned, once, in the rotary direction of the main shaft *a* and, then, in opposite direction thereto. Thereby, the speed of the driving chain-wheel is once accelerated and then retarded in uniformly alternate fashion, so that the speed variations take place in a shockfree manner and after a sine curve.

What I claim, is:

1. The combination, in an apparatus for feeding paper sheets, comprising a main shaft, of a casing for a differential gearing loosely turnable on said main shaft, a toothed sector on said casing, another toothed sector in gear therewith, and an eccentric gearing intermediate said main shaft and said last-mentioned toothed sector adapted to set the latter in uniformly reciprocating motion.

2. In an apparatus for feeding paper sheets, in combination with a main shaft and with a loosely turnable casing for a differential gearing, comprising a toothed wheel keyed to the said main shaft, planet wheels provided in said turnable casing and driven by said toothed wheel, a sleeve loosely mounted on said main shaft, a toothed wheel fitted to said loosely mounted sleeve and in mesh with said planet wheels, an eccentric keyed to the said main shaft, a rod fixed to said eccentric, a lever arm, a second shaft, the said lever arm being linked to said rod and keyed to said sec-

ond shaft, a toothed sector on said loosely turnable casing, another toothed sector on said second shaft, both sectors being in mesh with each other and designed to set the said 5 loosely turnable casing in uniformly reciprocating motion.

In testimony whereof I have hereunto set my hand.

HANS PRAETZEL.
